PLASTIC CIGARETTE BOX

John Schwarz, Glendale, Calif.

Application July 2, 1956, Serial No. 42,123

Term of patent 14 years

(Cl. D85—2)

Figure 1 is a perspective view of the plastic cigarette box embodying my new design, with its lid in closed position, and

Figure 2 is a perspective view of the cigarette box with its lid in open position and an insert tray lifted out.

I claim:

The ornamental design for a plastic cigarette box, substantially as shown.
